UNITED STATES PATENT OFFICE.

CHARLES M. GREISING AND JOHN DAHLIN, OF ST. PAUL, MINNESOTA, ASSIGNEES TO
ST. PAUL TWINE COMPANY, A CORPORATION OF MINNESOTA.

SAFETY CONTROL MECHANISM FOR BOBBIN-WINDERS.

1,187,904.

Specification of Letters Patent. Patented June 20, 1916.

Application filed October 13, 1913. Serial No. 794,837.

To all whom it may concern:

Be it known that we, CHARLES M. GREISING and JOHN DAHLIN, citizens of the United States, and residents of St. Paul, in the county of Ramsey and State of Minnesota, have invented certain new and useful Improvements in Safety Control Mechanism for Bobbin-Winders, of which the following is a full, clear, and exact specification.

This invention relates to bobbin winders and more particularly to safety control mechanism associated therewith.

In the manufacture of twine there are three main stages, namely, the preparing of the fiber, the spinning of the fiber into twine, placing the same upon bobbins, and balling the twine. Twine filled bobbins from the spinning machines are placed on the balling machines, where the twine is removed from the bobbins and made up into balls. In many instances a ball is completed before the bobbin is completely unwound and the twine left on the bobbin is so short that it does not pay to start another ball. This being the case, the bobbin with its remaining relatively short length of twine is removed from the balling machine and sent over to a bobbin winding machine. Again, during the balling process it is sometimes found that portions of the twine on a bobbin are too loosely woven. When such is the case this bobbin is also sent over to a bobbin winding machine. Here all of the relatively short pieces of twine from the bobbins are spun onto another bobbin placed in the bobbin winding machine, the relatively short pieces being tied together. Also the strips of loosely bound twine are removed from the defective bobbins and the remaining good portion thereof wound on the new bobbin being formed. This is done to prevent waste. It is apparent, therefore, that in the operation of a bobbin winding machine it is necessary that the machine be started and stopped at frequent intervals. It has been found that operators of these bobbin winding machines become careless in starting and stopping such machines and in attempting to remove bobbins before the machines have been stopped, and as a result thereof are injured.

The object, therefore, of our invention is to render the operation of bobbin winding machines safer.

The invention is illustrated on the accompanying sheet of drawings, in which—

Figure 1 is a plan view of a bobbin winding machine embodying our invention; and, Fig. 2 is a side elevation of the same.

The various novel features of our invention will be apparent from the description and drawings and will be particularly pointed out in the appended claims.

Secured to any suitable support 10 is a base 11, secured to which are three bracket members 12, 13 and 14. Journaled in bearing portions 15 and 16 of the bracket members 12 and 13 respectively, is a spindle 17, upon which a bobbin 18 is placed for receiving twine. Mounted upon and secured to the spindle 17 is a collar 19 having a pin 20 which passes through an opening in the bobbin so that when the spindle is rotated the bobbin is rotated therewith. Also mounted upon the spindle 17 are a loose pulley 21 and a tight pulley 22 engaged alternately by a belt 23 which transmits motion to said pulleys from any suitable source. When the belt 23 is in engagement with tight pulley 22, motion is transmitted through a gear 24 which is secured to the spindle 17, said gear meshing with another gear 25, which is secured to one end of a worm 26, the latter being journaled in bearing portions 27 and 28 of brackets 13 and 14 respectively. When the worm 26 is actuated it gives a reciprocatory motion to a guide member 29 having a portion 29^a which engages the worm 26 and also an opening 30 for the reception of a rod 31 upon which the guide member 29 slides, the rod being secured to bracket members 13 and 14. The guide member 29 is also provided with an eye portion 32 through which twine is fed to the twine receiving bobbin 18 from a source of twine supply, which in this case is a bobbin 33 mounted loosely upon a stationary spindle 34 in a protective cage 35 having a hinged door 36. This cage, which is mounted upon a bracket 37, is provided with two long rollers 38 between which the twine passes as it is fed to the receiving bobbin.

Previous to our invention the bobbin winding machine was set in motion by taking hold of a belt shifter 39 and shifting it in one direction or the other, but in operating the machine in this manner it was found that operators became reckless in attempting

to remove the twine supplying bobbin 33 before the machine was stopped. In this way their hands were caught and sometimes injured. Again, with no cage around the 5 twine supplying bobbin, parts of the body have come into engagement with the rapidly moving bobbin and caused painful burns. In numerous other ways injuries have been caused by recklessness of operators. To 10 render the operation of this machine safer, the twine supplying bobbin has been placed within the cage 35 which is completely closed when the machine is in motion, and the machine at rest when the cage door is open. 15 In other words, a safety interlock has been provided between the bobbin actuating mechanism and the source of twine supply. In this particular case it takes the form of an adjustable link 40, one end of which is pivoted to an arm 41, which is secured to the lower portion of the cage door 36, the other end of the link being secured to an arm 42, which in turn is secured to a bent rod 43, the latter being in engagement with the belt 20 shifting rod 39. With the cage door 36 open the belt is in engagement with the loose pulley 21, with the connecting parts being as shown in full lines, reference being had particularly to Fig. 1. If it is desired to start 25 the machine, the same is accomplished by closing the cage door 36 which draws the link 40 to the right, swinging the arm 42 in a clockwise direction, as shown in Fig. 1, and shifting the belt 23 through the medium 30 of the belt shifter rod 39 onto the tight pulley, whereupon motion is transmitted to the bobbin 18 for receiving twine from the supply bobbin in the cage. At the same time motion is also transmitted through the gears 35 40 and 25 to the worm 26 for reciprocating the feeder guide member 29. With the machine in operation, the cage door of necessity being closed, it is impossible for the operator to be injured in any manner whatsoever 45 by getting mixed up with the twine supplying bobbin or by the twine wound thereon. Further, it is impossible for the

operator to remove the twine supplying bobbin until the machine has been shut off completely, for the reason that the door is provided with a cover 44 which will not permit removal of the bobbin 33 until the cage door has been completely opened, and, therefore, the machine completely shut off. In this way many accidents are avoided. 50 55

It is evident that there may be various modifications of our invention as herein particularly shown and described, and it is the intention to cover all such modifications which do not involve a departure from the 60 spirit and scope of the invention as set forth in the following claims.

What we claim as our invention and desire to secure by Letters Patent is:

1. In a bobbin winding machine, the combination of a receiving bobbin, means for actuating the same, a feeder bobbin, a cage therefor having a door, and an adjustable connection between said door and actuating mechanism by means of which said actuating mechanism is controlled by means of said door. 65 70

2. In a bobbin winding machine, the combination of a receiving bobbin, means for actuating the same, a feeder bobbin, a guard 75 therefor having a movable element, and a connection between said movable element and said actuating means for controlling the operation of said machine.

3. In a bobbin winding machine, the combination of a receiving bobbin, means for actuating the same, a feeder bobbin, a guard therefor having a door, and means controlled by the opening and closing of said door for controlling the operation of said actuating 80 85 means.

In testimony whereof we affix our signatures, in the presence of two witnesses.

CHARLES M. GREISING.
JOHN DAHLIN.
